[57] CLAIM

The ornamental design for a spinner for wheels, as
shown and described.

DESCRIPTION

FIG. 1 is a top, front perspective view of a spinner for
wheels showing my new design, in a three wing em-
bodyment;

FIG. 2 is a right side elevational view thereof;

FIG. 3 is a top plan view thereof;

FIG. 4 is a top, front perspective view of a spinner for
wheels showing my new design, in a two wing embodi-
ment;

FIG. 5 is a right side elevational view thereof; and,
FIG. 6 is a top plan view thereof.

The bottom of the two embodiments of the spinner for
wheels is understood to be plain and unornamented.
